DESIGN FOR AN UMBRELLA TABLE

William D. Connor, Jr., Laona, Wis.

Application June 17, 1940, Serial No. 93,056

Term of patent 3½ years

To all whom it may concern:

Be it known that I, William D. Connor, Jr., a citizen of the United States, residing at Laona, in the county of Forest and State of Wisconsin, have invented a new, original, and ornamental Design for an Umbrella Table, of which the following is a specification, reference being had to the accompanying drawing, forming part thereof.

The drawing is a perspective view of an umbrella table, showing my new design.

The top of the umbrella is of substantially the same pattern as the underneath portion.

I claim:

The ornamental design for an umbrella table, as shown and described.

WILLIAM D. CONNOR, JR.
